UNITED STATES PATENT OFFICE.

GROVER C. LUCAS AND MANNA M. PRATT, OF BATAVIA, IOWA.

ENGINE-REPAIR STAND.

Application filed January 17, 1921. Serial No. 437,812.

To all whom it may concern:

Be it known that we, GROVER C. LUCAS and MANNA M. PRATT, citizens of the United States, residing at Batavia, in the county of 5 Jefferson and State of Iowa, have invented certain new and useful Improvements in Engine-Repair Stands, of which the following is a specification.

This invention relates to an improved re-
10 pair stand for motor vehicle engines and has as one of its principal objects to provide a device of this character wherein an engine may be supported in different convenient positions accessible for different particular 15 work thereon.

The invention has as a further object to provide a stand having a swingingly mounted supporting head and wherein said head may be moved to one position for sustaining 20 an engine right side up, may be moved to another position for sustaining the engine inverted, and may be moved to a third position for sustaining the engine disposed horizontally.

25 And the invention has as a still further object to provide a device wherein an engine may be readily attached to or detached from the supporting head thereof.

Other and incidental objects will appear 30 hereinafter.

In the drawings—

Figure 1 is a perspective view of our im-
proved repair stand,

Figure 2 is a detail perspective view of 35 the supporting head of the stand,

Figure 3 is a side elevation showing an engine of conventional design supported right side up by the stand,

Figure 4 is an end elevation, particularly 40 bringing out the manner in which the engine is attached to the supporting head employed, and

Figure 5 is a fragmentary end elevation showing the engine disposed horizontally.

45 In constructing our improved stand we employ pairs of diverging supporting legs 10. Between the upper ends of the legs of each pair is secured a substantially triangular block 11 and connecting the pairs of legs 50 are cross brace rods 12 while between the lower end portions of the legs of each pair is arranged a cross rod 13 upon which is rested a suitable supporting shelf 14 adapted to receive various tools or parts of the en- 55 gine being repaired. Extending between the upper end portions of corresponding legs at

one side of the stand is a cross bar 15 and pivoted upon one of the legs at the opposite side of the frame is a rod 16 normally hanging downwardly in inactive position. This 60 rod is provided at its free end with a hook 28 and slideable upon the rod is a spring pressed keeper comprising a sleeve 29 carrying a locking dog 30 normally extending across the hook. 65

Fitting through the blocks 11 is a cross rod 17 and mounted to swing upon said rod is a supporting head comprising a substantially U-shaped body bar 18 to which is secured a similarly shaped bracket bar 19 lying 70 at substantially right angles to the body bar. The bracket bar is provided with spaced openings 20 and secured to the lower ends of the bracket bar is a base bar 21 the end portions of which are curved laterally downward and are provided with reduced 75 studs 22.

In Figures 3, 4 and 5 of the drawings, we have shown the different positions in which our improved stand is adapted to support 80 an engine, an engine of conventional design being illustrated, and in this connection it may be observed that the device is particularly adapted for use in connection with engines commonly known as the Ford. The 85 engine block is indicated at 23, the head at 24, and the crank case at 25, the block and crank case being provided with mating flanges 26 through which are engaged bolts 27 securing the crank case to the block. 90

In practice, a pair of the bolts 27 at one side of the engine are removed as is also the cylinder head outlet connection. The studs 22 of the base bar 21 of the supporting head of the stand are then fitted through the 95 empty bolt holes of the flanges 26 of the engine when a pair of bolts are, as particularly shown in Figures 3 and 4, fitted through the holes 20 of the bracket bar of the head and threaded into the bolt holes 100 at opposite sides of the outlet orifice in the engine block. This done, the engine will be securely connected to the supporting head. Accordingly, the head may be swung to sustain the engine, as shown in Figure 3, at one 105 side of the stand, when the cylinder head may be readily removed as may also the transmission cover so that access may be easily had to the valves for grinding the valves while also, access may be easily had 110 to the transmission of the engine. By swinging the supporting head to lie at the oppo-

site side of the frame, the engine will be shifted to rest upon the cross bar 15 of the stand when the crank case may be readily removed, thus rendering the connecting rod bearings of the engine readily accessible as well as the main crank shaft bearings. In order that the operation of fitting the engine piston as well as tightening the bearings may be readily accomplished, the engine is, 10 as shown in Figure 5, swung to a horizontal position. To sustain the engine in this position, the rod 16 is swung upwardly when, after retracting the sleeve 29, the hook 28 is engaged through one of the bolt holes of the base flange of the engine block from the outer side of said flange. The sleeve is then released when the dog 30 will be moved to confront the flange at its inner side for locking the hook engaged with the flange so 20 that the engine will thus be rigidly held by the rod against movement in either one direction or the other. It will accordingly be seen that we provide a stand of highly effective construction as well as a device which 25 will greatly facilitate the task of properly and thoroughly repairing a motor vehicle engine.

Having thus described the invention, what is claimed as new is:

- 30 1. An engine repair stand including a stand body, an engine supporting head mounted to swing thereon and movable to lie at opposite sides of the stand body selectively, a rod pivoted upon the stand body and provided at its free end with a hook engageable through a bolt opening in the

base flange of an engine upon the head for holding the engine in horizontal position sustained by the head, and a spring pressed keeper upon the rod to coact with said flange 40 for locking the hook against disengagement therefrom.

2. An engine repair stand including a stand body, a cross rod carried thereby, a body bar mounted to swing upon said rod, 45 a bracket bar secured to the body bar, and a base bar carried by the bracket bar to form an engine supporting head.

3. An engine repair stand including a stand body, a cross rod carried thereby, a 50 substantially U-shaped body bar mounted to swing upon said rod, a substantially U-shaped bracket bar secured to the body bar at substantially right angles thereto, and a base bar extending between the free ends 55 of the bracket bar to form an engine supporting head and provided at its ends with studs.

4. An engine repair stand including pairs of diverging supporting legs, blocks clamped 60 between the upper ends of the legs of said pairs rigidly spacing the legs at their upper ends and upstanding from the legs to form bearings, a cross rod journaled through said bearings, and an engine supporting head including a body bar journaled at its ends upon said rod adjacent the blocks for swingingly supporting the head.

In testimony whereof we affix our signatures.

GROVER C. LUCAS. [L.S.]
MANNA M. PRATT. [L.S.]
